DISPLAY COUNTER OR THE LIKE

Saul Gershon, 7749 Whitsett Ave.,
North Hollywood, Calif

Filed May 16, 1962, Ser. No. 70,158

Term of patent 3½ years

(Cl. D80—11)

FIG. 1.

FIG. 2.

FIG. 1 is a front perspective view taken at one end of a display counter, or the like showing my new design, the rear and end not disclosed being essentially the same as the front and end shown, respectively; and

FIG. 2 is a top plan view thereof.

I claim:

The ornamental design for a display counter or the like, as shown and described.
